UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

THIRD-POINT SUPPORT FOR BRAKE-BEAMS.

1,175,575.

Specification of Letters Patent. Patented Mar. 14, 1916.

Application filed January 5, 1916. Serial No. 70,474.

To all whom it may concern:

Be it known that I, CHARLES HAINES WILLIAMS, a citizen of the United States, residing at city of Chicago, State of Illinois, have invented a certain new and useful Improvement in Third-Point Supports for Brake-Beams, of which the following is a full, clear, and exact description, such as will enable others skilled in the art to which it appertains to make and use the same, reference being had to the accompanying drawings, forming part of this specification, in which—

Figure 1 is a side elevational view of a third point support for brake beams, the same being applied to a beam. Fig. 2 is a detail view of the support. Fig. 3 is a side elevational view of a modified form of the support. Fig. 4 is a top plan view of the structure shown in Fig. 3. Fig. 5 is a side elevational view of another form of the strut. Fig. 6 is a detail view of the support shown in Fig. 5. Fig. 7 is a side elevational view of another modified form of the support. Fig. 8 is a detail view of the form shown in Fig. 7. Fig. 9 is a detail view of another modified form of the support.

This invention relates to a new and useful improvement in third point supports for brake beams such as disclosed in Patent No. 997,888 granted to Charles H. Williams, Jr., on July 11, 1911.

It has been found in practice that the third point support in the form of a pivoted member arranged at the center of the brake beam at the end of the truss, and which pivoted member co-operates with the inclined portion of the supporting track, will sometimes become accidentally displaced by being tilted back over the top of the strut and thereby impair the object and purpose of the third point support.

It is the purpose of the present invention to provide means on the pivoted member constituting the third point support which will prevent this accidental displacement.

In the drawings, in Figs. 1 and 2, I have shown conventionally the spring plank of a truck which is indicated at 1 and to which 50 is secured the inclined track support 2. 3 is the head of a brake beam and 4 the usual hanger thereof. 5 is the brake beam strut and 6 the tension member. 7 is the third point support pivoted at the outer end of 55 the strut between the two lugs constituting

the nose of the strut. This support is intended to ride upon the inclined track support and the parts above described are intended to operate as disclosed in the Williams patent before mentioned. The third 60 point support 7, as shown in Fig. 1, is provided with an upward extension 8 having lateral projections 9 which are designed, in the event of any tendency of the third point support to tilt over the end of the strut, to 65 contact with the nose lugs and prevent such tilting action.

In Figs. 3 and 4 I have shown the third point support as being provided with two lugs 10, which serve to prevent the tilting 70 action of the third point support, but like the construction shown in Fig. 1, these lugs permit a certain range of pivotal movement of said third point support. It is preferable to employ two lugs rather than one, 75 because by so doing it is unnecessary to exercise any care in the exact arrangement of the third point support between the nose lugs.

In Figs. 5 and 6, I have shown another 80 form of my invention in the nature of extensions or horn-like projections 11 which are inclined upwardly away from the track support so as not to add to the friction of the movement of the third point support. 85 These horn-like projections will, under ordinary service conditions, prevent any excessive tilting action of the third point support.

In Figs. 7 and 8, I have shown another 90 modified construction designed particularly for use in connection with brake beams in which third point support is pivotally mounted on the strut underneath instead of directly 95 in advance of the tension member, as shown in Figs. 1, 3 and 5. In this modified form shown in Figs. 7 and 8, the lugs 11^a, which restrain excessive tilting action, are substantially T-shaped and are designed to contact with the nose lugs in the event that the 100 third point support attempts to assume an abnormal position. In Fig. 9 the lugs 12 are substantially the same as shown in Figs. 7 and 8 except that they are not T-shaped.

In the patent to W. F. Kiesel, Jr., No. 105 997,922, dated July 11, 1911, there is shown a third point support provided with lips which embrace the inclined track, but in order to remove the truck beam from the truck, it is necessary by this construction 110

to also remove the inclined track; and in the patent to E. A. Le Beau, No. 990,889, dated May 2, 1911, there is shown a third point support which embraces the inclined track, the latter being refolded to avoid the objection mentioned with respect to the Kiesel patent. The advantage of the Le Beau construction, however, only obtains with respect to outside hung beams, and where the beams are inside hung, especially in trucks with narrow wheel bases, the Le Beau construction possesses the disadvantage of the Kiesel construction in that it is necessary to remove the inclined track support in order to unhang the beam and move it from the truck. The present improvement is to enable the dismantling or unhanging of the beam in all classes of trucks, regardless of whether or not the beam is inside or outside hung, and at the same time provide means whereby any portion of the third

point support will be prevented from riding the strut and thus becoming inoperative for the purposes for which it is intended.

What I claim is:

A third point support for brake beams comprising a pivoted shoe suspended from a part of the beam, said shoe having equilateral means located adjacent its pivotal point for coöoperating with the brake beam to prevent said pivoted shoe from occupying an abnormal position, the equilateral means referred to enabling said pivoted shoe to be introduced into either a right or left-hand beam. 35

In testimony whereof I hereunto affix my signature in the presence of two witnesses, this 28th day of December, 1915.

C. HAINES WILLIAMS.

Witnesses:

E. T. WALKER,
M. F. HUNTOON.
